VALVE-SPRING LIFTER TOOL

Herman L. Durivage, Toledo, Ohio

Application July 15, 1933, Serial No. 680,549

1 Claim. (Cl. 29—86.3)

My invention relates to tools of an accessory character which, by reason of their application, assist and expedite the use of other tools and thereby render the performance of the particular job an easier and speedier task. The invention particularly relates to a valve-spring lifting tool and provides a device for quickly and easily relieving the valve-spring pressure on the stem pin of the valve-spring lock to permit withdrawal of the pin and subsequent removal of the valve head and stem for purposes of grinding or repair.

The invention is particularly adapted for use on poppet valves of the well known type and has, for its object, to provide an element for engaging one end of the valve tappet guide and another element for engaging the valve-spring washer, the said elements being movable with respect to one another by a means controlled and operated at a point remote from, and easily accessible to, the user. The invention therefore eliminates much of the difficulty and expense involved in valve removing jobs.

The invention also provides means for maintaining the valve-spring in a position of relief as related to the stem pin whereby the mechanic may, without the exercise of haste or of great manual strength, remove the stem pin, or, in the case of reassembly, insert the stem pin, thus readily disassembling and reassembling the valve.

The invention has for its particular object to provide a foot element adapted to engage the end of the tappet guide approximating the valve spring, and a jaw element adapted to engage the valve-spring washer, and means interconnecting said foot and jaw elements for progressively moving the elements with respect to each other, said means being operated or driven by a handle located at a point easily accessible to the user.

The invention consists in other features and advantages which will appear from the following descriptions and upon examination of the drawing. Structures containing the invention may partake of different forms and may be varied in their details and still embody the invention. To illustrate a practical application of the invention, I have selected a valve-spring lifter tool embodying the invention, as an example of the various structures and details thereof that contain the invention, and shall describe the selected structure hereinafter, it being understood that variations may be made without departing from the spirit of the invention. The particular structure selected is shown in the accompanying drawing.

Fig. 1 of the accompanying drawing illustrates a view of the valve-spring lifter as applied

to a particular poppet valve-spring job. Fig. 2 illustrates an enlarged side view of the valve spring lifter shown in Fig. 1. Fig. 3 illustrates a view taken at one end of the valve-spring lifter. Fig. 4 illustrates a front view of the valve-spring lifter.

As is well known, mechanical repairs, for example, on internal combustion engines which involve the removal of the poppet valves for purposes of grinding or replacement, are costly and difficult. One of the major factors which contributes to the cost is the fact that the valves are usually located with respect to other parts of the engine and its frame at a point where ready accessibility and freedom of operation is practically impossible. The valves are usually locked in position by means of a washer and pin against which the valve-spring bears and might be more readily removed if the pressure exerted by the valve-spring were removed or diverted from the said pin. Various lever-acting tools have been designed to perform this function, but in the main have been objectionable for the reason that the available space in which the tool operating part may be swung or operated is usually limited by the occupancy of other parts of the engine and for the reason that the attention of the operator must be maintained on the said tool while removing the pin to prevent the spring from escaping the influence of the lifting tool, thus limiting the full use of the operator's attention and hands in the removal of the pin from the valve stem.

The valve-spring lifting tool provided by my invention has a generally U-shaped foot which is adapted to rest upon and substantially clasp the end of the tappet guide. The foot is connected to one end of a rack member and may be designed to be removable therefrom for purposes of substitution of similar foot members of various gauge and dimension, dependent upon the size of the tappet guide and tappet head. A bifurcated jaw member having flange portions, and adapted to engage and substantially clasp the valve-spring washer, is slidably supported on the rack member by means of a movable frame. The movable frame is provided with a suitable pinion gear, the teeth of which are adapted to mesh with the teeth of the rack member and thus, upon rotation of the pinion gear, the bifurcated jaw will be moved relative to the foot. The pinion gear is suitably keyed to a stub shaft having a yoked or Y-shaped end portion. A discular link is pivotally supported between the legs of the Y-shaped end portion. A handle member having a lever arm, the end of which is yoked or Y-shaped, is pivotally

connected to the discular link at a point at right angles to the points of connection of the stub shaft and in a common plane therewith. Thus the handle is connected to the pinion shaft for operation, regardless of the position of the handle with respect to the pinion shaft and the handle may be rotated to rotate the shaft, driving the frame over the rack and moving the jaw relative to the foot.

10 In the preferred form of construction shown, with respect to a poppet valve-spring, for purposes of illustration, the valve-spring lifter 1 has a U-shaped or bifurcated foot 2 which is removably connected to an end of a rack member 3, as by a bolt and nut assembly 5. The foot 2 preferably has skirt or flange portions 6 which extend below the edges of the foot, forming a partial recess 8, which is adapted to receive and substantially clasp a tappet guide 10, such as is illustrated in Fig. 1. Where the tappet guide varies in size, requiring a foot member of another size, substitution thereof may be obtained by merely removing the bolt and nut assembly 5 and substituting another foot member 2.

15 25 In order to provide means for relieving the pressure of the valve-spring, such as the spring 11 shown in Fig. 1, upon the stem pin, such as the stem pin 12, to permit the withdrawal of the pin 12, a bifurcated jaw 15 is provided and is removably connected to a movable frame 16, as by the screws 20. The frame 16 partakes of general U-shape and is adapted to receive the rack member 3 in the web thereof, through which the rack member may slide, and in that connection the frame 16 operates as a guide to maintain the rack and jaw in a relatively constant angle.

The jaw 15, like the foot 2, is provided with skirted or flanged portions 17 forming a partial recess 18, which is adapted to receive and substantially clasp a valve-spring washer, such as the washer 19 shown in Fig. 1. Various sizes of jaws 15 may be substituted to meet the varying exigencies of practice by removal of the screws 20. Thus it will be seen that as the jaw 15 is moved along the rack 3, the pressure of the spring 11 will be borne by the jaw 15 and relieved as against the pin 12, permitting easy removal of the pin.

40 45 50 55 In order to move the jaw 15 and frame 16 with respect to the foot 2 and along the rack 3, a pinion gear 21 is rotatably supported in the frame 16 on a stub shaft 22, to which it may be suitably keyed, as by the pin 23. The gear 21 is supported so that its teeth 24 are located in meshing relation with the teeth 25 of the rack 3. Thus upon rotation of the shaft 22, the frame 16 will be caused to move progressively over the rack member 3 and relative to the foot 2.

The shaft 22 is connected for rotation to a suit-

able manually operable handle 26 by a means enabling rotation of the shaft at a point conveniently remote from the jaw 15 and therefore easily accessible to the user. The shaft 22 has a bifurcated end portion 27 forming legs 28. A discular link 29 is supported, as by the pin 30, between the legs 28. The handle 26 has a lever arm 31, the end of which is bifurcated, as at 33, forming legs 34. The legs 34 are each pivotally connected to the link 29 by stub pins 36, at points substantially in a common plane with the pin 30 but right-angles thereto. It will be readily apparent that the handle 26 may be located at almost any angle with respect to the shaft 22 and be rotated to rotate the pinion gear 21 as described.

80 85 90 95 100 If desired, a suitable pawl 37 may be pivotally supported, as by the pin 38, on the frame 16 and be adapted to engage the teeth 24 of the pinion as the jaw 15 is moved away from the foot. The movement of the jaw may thus be made periodic, and the jaw will be locked in position to hold the spring. The pawl may be provided with a suitable trip bar 39 for disengaging the pawl from the pinion teeth.

105 110 115 120 125 The valve-spring lifting tool may be readily used in reassembly of the valve, as is appreciated by those skilled in the art. One end of the spring 11 may be placed in its normal position with respect to the valve stem guide, and the other end engaged by the jaw 15. The handle 26 may then be operated to compress the spring as before, and the pin 12 placed in position through the valve stem.

I claim:

130 135 140 145 150 A valve-spring lifter comprising a bifurcated foot element having depending skirt portions adapted to receive within their confines the valve tappet; a bifurcated jaw element having upstanding skirt portions adapted to receive within their confines the valve-spring washer, a rack member, the foot element having an opening adapted to slidably receive one end of the rack member, a bolt for removably locking the said end of the rack member in the said opening, a U-shaped frame, bolts for removably connecting the jaw member to the U-shaped frame, the rack member disposed for reciprocatory movements in the web portion of the U-shaped frame, a pinion gear rotatably mounted on the U-shaped frame and disposed for engagement with the rack, a shaft keyed to the pinion gear, manually operable means connected to the shaft for rotating the pinion gear, a pawl pivotally mounted on the frame and biased against the pinion gear to normally restrict the movement of the pinion gear to but one direction, and a hand operated lever for overcoming said bias and for releasing the pinion gear.

HERMAN L. DURIVAGE.
